UNITED STATES PATENT OFFICE.

JOHN H. T. MILLS AND VIRGIL H. MILLS, OF HUBBARD, TEXAS.

HYDROCARBON-BURNER.

1,004,292.

Specification of Letters Patent. Patented Sept. 26, 1911.

Application filed November 26, 1910. Serial No. 594,317.

To all whom it may concern:

Be it known that we, JOHN H. T. MILLS and VIRGIL H. MILLS, citizens of the United States, residing at Hubbard, in the county 5 of Hill and State of Texas, have invented certain new and useful Improvements in Hydrocarbon-Burners, of which the following is a specification.

This invention relates to oil burners and 10 more particularly to that class of burners in which a jet of steam or air is employed for atomizing the fuel at the burner tip.

The object of the invention is to provide a burner of simple and durable construction, 15 capable of producing a maximum amount of heat with a minimum consumption of fuel.

A further object is to provide means for blowing out any foreign deposits that may 20 lodge in the steam or air outlet at the burner tip, without the necessity of shutting down the burner or in any manner interfering with the operation thereof.

A further object is to provide means whereby the fuel supply pipe may be quickly 25 detached from the rear end of the burner so as to permit the fuel conductor to be readily removed from the burner and cleaned when necessary.

A further object is to provide a burner 30 having a relatively large opening or clearance at the tip thereof to assist in atomizing the oil, the outer end of the oil conductor being beveled and preferably extended slightly beyond the cap of the steam or air outlet 35 to prevent the oil from coming in contact therewith.

A further object is to provide means for centering the oil conductor within the casing, and means for adjusting the cap of the 40 steam or air pipe with respect to the bevel end of the oil conductor so as to produce a narrow steam outlet and also to prevent back pressure of the steam on the liquid fuel.

A still further object of the invention is 45 generally to improve this class of devices so as to increase their utility, durability and efficiency.

Further objects and advantages will appear in the following description, it being understood that various changes in form, proportions and minor details of construction may be resorted to within the scope of the appended claims.

For a full understanding of the invention

and the merits thereof, reference is to be had 55 to the following description and accompanying drawings, in which:

Figure 1 is a longitudinal sectional view of a hydro-carbon burner constructed in accordance with our invention; Fig. 2 is a side 60 elevation of the same; Fig. 3 is a top plan view; Fig. 4 is a transverse sectional view taken on the line 4—4 of Fig. 1; Fig. 5 is a detail perspective view of the pivoted frame and locking bail detached; Fig. 6 is a detail 65 vertical sectional view illustrating a modified form of the invention.

Corresponding and like parts are referred to in the following description and indicated in all the views of the drawings by the same 70 reference characters.

The improved oil burner forming the subject matter of the present invention comprises a tubular member or casing 5 preferably cylindrical in shape, as shown, and having 75 its inner end threaded for engagement with the correspondingly threaded end of a coupling 6, the latter being provided with means for connection with a steam or air pipe, indicated at 7. Disposed within the 80 casing 5, is an oil conductor 8 having its outer end inclined or beveled at 9 and its inner end extended within and detachably secured to a sleeve 10, the exterior walls of the conductor 8 being spaced from the casing 11 which communicates with the supply pipe 7 and through which fluid from the pipe 7 is conducted to the burner tip for the purpose of atomizing the fuel. 90

Threaded in one end of the coupling 6, is a collar or bushing 12 having its outer end provided with a flange 13 spaced from a corresponding flange formed on the coupling 6 to produce an intermediate seating 95 groove 14. Disposed at the rear end of the sleeve 10, is a casting 15 having its rear end closed and provided with a depression or socket 16 and its front end reduced to form a nipple 17 extending within the sleeve 10, the side walls of the casting being provided with an opening to which is connected in any suitable manner a supply pipe 18, through which oil is conducted to the burner tip. Seated in the groove 14, is a ring 19 105 having secured to or formed integral therewith a transverse bar 20 and provided at its opposite ends with laterally extending lugs

21 on which is pivotally mounted a rocking frame 22. Extending vertically from the upper end of the frame 22, is an operating lever 23, while a lug 24 depends from the 5 bottom of the frame for connection with one end of a coil spring 25; the other end of which is secured in any suitable manner to a pin 26 carried by the coupling 6.

Arranged at the burner tip, is a cap 27 10 having oppositely disposed perforated lugs 28 to permit the passage of connecting rods 29, the rear ends of said rods being formed with eyes 30 adapted to engage suitable trunnions 31 secured to the side walls of 15 the frame 22, said rods being retained in position on the trunnions by cotter pins or similar fastening devices 32. The outer ends of the rods 29 are threaded for engagement with clamping nuts 33, one of which bears 20 against each side of the adjacent lug 28. The cap 27 is provided with an opening to accommodate the conductor 8, while the interior walls of the opening in the cap are undercut or beveled at 34 to correspond to 25 the inclination or bevel 9 of the conductor, thus to permit the discharge of steam or air under pressure at the burner tip, as before stated.

It will here be noted that the outer end 30 of the conductor 8 is preferably of the same diameter as the inner end thereof, thus to produce a relatively large opening or clearance at the burner tip and assist in atomizing the oil. It will also be noted that the 35 beveled end 9 of the conductor preferably projects slightly beyond the outer face of the cap 27 to prevent the oil from coming in contact therewith and also to prevent back pressure of the steam on the fuel. Suitable 40 pins 35 are threaded in the casing 5 and bear against the conductor 8 for the purpose of centering said conductor within the casing and producing a steam or air passage of uniform width around the beveled end of the 45 oil conductor. Thus it will be seen that by moving the operating lever 23 in the direction of the cap 27, the latter may be spaced from the adjacent end of the casing 5 so that the steam or air from the pipe 7 may 50 be utilized for blowing out or cleaning the burner thus to remove any foreign particles that may find lodgment at the burner tip without shutting down the burner or in any manner interfering with the operation 55 thereof.

Extending laterally from the opposite sides of the ring 19, are pins 36 on which is pivotally mounted a yoke or bail 37, the latter being provided at its free end with 60 a threaded opening 38 in which is mounted for rotation a clamping screw 39. The free end of the clamping screw 39 is pointed and adapted to enter the depression 16 in the casting 15 so that by rotating the screw 39 65 in the bail until the pointed terminal of

said screw engages the recess 16, the casting 15 will be clamped within the sleeve 10. A suitable gasket 40 is preferably interposed between the flange on the bushing 12 and a stop flange 39' on the sleeve 10 to prevent 70 leakage. It will also be seen that by releasing the clamping screw 39 and swinging the bail 37 upwardly in the direction of the lever 23, the casting 15 may be detached from the sleeve 10 and the latter, together 75 with the conductor 8, removed from the casing 5 to facilitate cleaning the parts when necessary. By having the conductor 8 threaded in the sleeve 10, the bevel end 9 of said conductor may be adjusted with 80 respect to the undercut face of the cap 27 so as to vary the width of the steam passage at the burner tip, by merely rotating said conductor. A similar result may be effected by rotating the outer casing 5 on 85 the coupling 6.

Attention is here called to the fact that the bail 37 is pivotally mounted on the ring 19, so that the casting 15 and its associated 90 parts may be detached from the burner and the conductor withdrawn from the casing 5 without affecting the operating lever 23 or cap 27.

A clamping nut 41 is preferably threaded on the clamping screw 39 so as to lock the 95 screw against rotation after the latter has been adjusted to clamp the casting 15 in position on the rear end of the burner.

The cap 27 is preferably formed with a rearwardly extending sleeve 42 which projects within the fluid chamber 11 and forms 100 a guide for the cap when the latter is adjusted laterally with respect to the casing either to effect the cleaning or blowing out 105 of the burner or to regulate the width of the steam passage at the burner tip.

In Fig. 6 of the drawings, there is illustrated a modified form of the invention in which the inner end of the fuel conductor 8' 110 is threaded on a gland or bushing 43, the construction and operation of the device being otherwise similar to that shown in Fig. 1 of the drawings.

Having thus described the invention, what is claimed as new is:

1. An oil burner including a casing, an oil conductor disposed within and spaced from the casing to form an intermediate fluid chamber, the outer wall of the outer end of the conductor being beveled, a sleeve 120 carried by the inner end of the conductor, a cap forming a partial closure for the fluid chamber and having its central portion provided with an opening, the walls of which are undercut and spaced from the beveled end of the conductor, means for adjusting the cap longitudinally with respect to the conductor, a casting engaging the sleeve and provided with a fuel inlet, and a swinging bail having a clamping device adapted to 125 130

- engage the casting for holding the latter in position upon the sleeve.
2. An oil burner including a casing, an oil conductor disposed within and spaced from the casing to form an intermediate fluid chamber, means extending through the casing and engaging the conductor for centering the latter with respect to the casing, a cap forming a partial closure for the outer end of the fluid chamber, a lever pivotally mounted on the casing, and a connection between the cap and lever for adjusting the cap with respect to the adjacent end of the casing when the lever is operated.
- 15 3. An oil burner including a casing, an oil conductor disposed within and spaced from the casing to form an intermediate fluid chamber, the outer end of said conductor being beveled, a sleeve secured to the inner end of the conductor and loosely fitting within the casing, a casting fitting within the sleeve and having means for connection with an oil supply pipe, a cap forming a partial closure for the fluid chamber and having an opening therein, the walls of which are undercut and spaced from the beveled end of the conductor, means for adjusting the cap with respect to said beveled end of the conductor, and a swinging bail having means for engagement with the casting for clamping the latter on the sleeve.
4. An oil burner including a casing, an oil conductor having a beveled end disposed within and spaced from the casing to form an intermediate fluid chamber, a bushing in said casing, a sleeve loosely mounted within the bushing and connected with the inner end of the conductor, a casting engaging the sleeve and provided with means for connection with an oil supply pipe, a ring mounted on the bushing and provided with laterally extending pins, a bail pivotally mounted on the pins, a clamping screw carried by the bail and adapted to engage the casting for clamping the latter in engagement with the sleeve, and a cap on the end of the casing having an opening formed therein, the walls of which are undercut and spaced from the beveled end of the conductor.
5. An oil burner including a casing, an oil conductor disposed within and spaced from the casing to form an intermediate fluid chamber, the outer end of said conductor being beveled, a cap forming a partial closure for one end of the fluid chamber and having an opening, the walls of which are undercut and spaced from the beveled end of the conductor, said cap being provided with oppositely disposed perforated lugs, a swinging frame supported on the burner and provided with laterally extending trunnions, connecting rods having their inner ends pivotally mounted on the trunnions on the frame and their outer

ends extending through the perforations in the lugs on the cap, said frame having one end thereof extended to form an operating lever and its other end provided with a depending arm, a spring forming a connection between the arm and casing, and means for admitting fuel to the rear end of the oil conductor.

6. An oil burner including a casing, a coupling secured to the casing and having means for connection with a source of fluid supply, an oil conductor extending within and spaced from the casing to form an intermediate fluid chamber communicating with the fluid supply, a bushing engaging the coupling and having a flange spaced from the adjacent end of the coupling to form an intermediate seating groove, a sleeve loosely mounted in the bushing and secured to the adjacent end of the conductor, a casting fitting within the sleeve and provided with means for connection with a source of oil supply, a ring seated in said groove and provided with oppositely disposed pins, a frame pivotally connected with the ring, a cap forming a partial closure for the outer end of the fluid chamber, a connection between the cap and frame, one end of the frame being extended to form an operating lever, and a bail pivotally mounted on the pins of the ring and provided with a clamping screw adapted to engage the adjacent end of the casting for clamping the latter in engagement with the sleeve.

7. An oil burner including a casing, a bushing secured to one end of the casing, an oil conductor disposed within and spaced from the casing to form an intermediate fluid chamber, a cap disposed at one end of the fluid chamber, a ring engaging the bushing and provided with a transverse bar, a frame pivotally mounted on said bar, a connection between the frame and cap, a spring operatively connected with one end of the frame for normally and yieldably holding the cap in engagement with the adjacent end of the casing, the other end of said frame being provided with a lever, a casting having a fuel inlet communicating with the interior of the oil conductor, and means mounted on the ring and engaging the casting for holding the latter in position.

8. An oil burner including a casing, an oil conductor disposed within and spaced from the casing to form an intermediate fluid chamber, the outer end of the conductor being beveled, a cap having an opening to accommodate the oil conductor and having the walls thereof undercut to conform to and spaced from the beveled end of the conductor, a sleeve secured to the inner end of the conductor, a casting engaging the sleeve and having means for connection with a source of fuel supply, means for adjusting the cap with relation to the casing, and

means independent of the cap adjusting means for clamping the casting in engagement with said sleeve.

9. An oil burner including a casing, an oil conductor disposed within and spaced from the casing to form an intermediate fluid chamber and having its outer end unobstructed to form a clearance and its side walls at said outer end beveled, a cap extending across one end of the steam chamber and having an opening therein, the walls of which are undercut and inclined to conform to and spaced from the beveled end of the conductor, pins threaded in the casing and engaging the conductor for centering the latter within said casing, means for adjusting the cap with respect to the casing, a sleeve carried by the inner end of the conductor, a casting engaging the sleeve, and means engaging the casting for detachably securing said casting in position on the sleeve.

10. An oil burner including a casing, an oil conductor disposed within and spaced from the casing to form an intermediate fluid chamber, a cap, a bushing mounted on the casing, a ring engaging the bushing, a frame pivotally mounted on the ring and provided with an operating lever, a connection between the frame and cap for adjusting the latter with respect to the casing, a casting having a fuel inlet communicating with the interior of the oil conductor, and means pivotally mounted on the ring and independent of the frame for clamping the casting in position.

11. An oil burner including a casing, an oil conductor disposed within and spaced from the casing to form an intermediate fluid chamber, a cap forming a partial closure for the fluid chamber and having an opening to accommodate the outer end of the oil conductor, a casting having a fluid inlet communicating with the interior of the

conductor, means for adjusting the cap with relation to the casing, and means independent of the cap adjusting means for clamping the casting in position.

12. An oil burner including a casing, an oil conductor disposed within and spaced from the casing to form a fluid chamber, a cap forming a partial closure for the fluid chamber, a lever, a connection between the cap and lever, and means operatively connected with said lever for yieldably supporting the cap in engagement with the adjacent end of the casing.

13. An oil burner including a casing, an oil conductor disposed within and spaced from the casing to form a fluid chamber, a cap forming a partial closure for the fluid chamber and having an opening to accommodate the outer end of the conductor, a casting having a fuel inlet communicating with the interior of the conductor, a lever, a connection between the cap and lever for adjusting the cap relative to the casing, means operatively connected with the lever for yieldably holding the cap in engagement with the casing, and means independent of the lever and engaging the casting for clamping the latter in position.

14. An oil burner including a casing having independent oil and fluid chambers, a cap forming a partial closure for one of said chambers, a lever, a connection between the lever and cap, and means operatively connected with the lever for normally and yieldably holding the cap in engagement with the casing.

In testimony whereof, we affix our signatures in presence of two witnesses.
